UNITED STATES PATENT OFFICE.

ROY S. LATIMER, OF TROY, NEW YORK, ASSIGNOR TO THOMAS H. LATIMER, OF SARATOGA SPRINGS, NEW YORK.

FOLDING MACHINE.

1,416,099.

Specification of Letters Patent. Patented May 16, 1922.

Application filed April 12, 1917. Serial No. 161,598.

To all whom it may concern:

Be it known that I, Roy S. LATIMER, a citizen of the United States, residing at Troy, county of Rensselaer, and State of 5 New York, have invented certain new and useful Improvements in Folding-Machines, of which the following is a specification.

Reference may be had to the accompanying drawings, and the reference characters 10 marked thereon, which form a part of this specification. Similar characters refer to similar parts in the several figures therein.

This invention relates to the heating of parts of various machines adapted for the 15 operation of said heated parts upon successive articles.

The invention is particularly adapted for the heating of said parts or members of machines for folding the edges of fabric blanks 20 in the manufacture of collars, cuffs, and the like.

In machines of this class it is found necessary to heat one or more of the parts or members which come into contact with the 25 fabric blanks in order to press or iron a fixed fold in the edge of the finished blank. The successive blanks take up more or less of the heat during the folding and pressing operations.

As heretofore practiced it has been deemed necessary to maintain constantly during the period of operation of the machine a sufficiently high temperature in the heated member or members to insure against a material 35 reduction in temperature of such part or parts by the loss of heat taken from the machine by the successive articles at the maximum speed of the machine which is usually dependent upon the capacity of the operator.

With such methods of heating as have heretofore been employed, failure for any cause to continue the operation of the machine at such maximum speed results in increased temperature of the heated part or 45 parts, such as to burn or scorch the articles. It is thus necessary when the operation of the machine is interrupted for any cause for the operator to cut off or diminish the supply 50 of heat, and when the operator fails to do this, as is often the case, the machine becomes so overheated as to scorch and injure the work.

The principal object of the present invention is to impart to the heated part or parts

of the machine heat-units in substantially the ratio in which heat-units are taken from said part or parts in the operation of the machine upon successive articles, whereby the loss of heat-units caused by the operation upon successive articles is at once compensated for by imparting to the heated part or parts of the machine a substantially like value of heat-units; and the invention consists in the hereinafter described method and 60 apparatus for accomplishing such object, and other objects which will appear in connection with the following description.

Fig. 1 of the drawings is a top plan view of a folding-machine made in accordance 70 with my invention.

Fig. 2 is a diagram of the wiring for the electric heating of the machine.

Fig. 3 is a view in end elevation partly in vertical section of the machine with the tem- 75 plet lowered upon the bed.

Fig. 4 is a similar view of a part of the machine on a larger scale showing the templet raised.

Fig. 5 is a horizontal section taken on the 80 broken line 5—5 in Fig. 4, through the templet-carrying shaft.

Fig. 6 is a bottom plan view of the electrically heated bed-plate.

Fig. 7 is a vertical longitudinal section of 85 the same taken on the broken line 7—7 in Fig. 6.

Fig. 8 is a bottom plan view of the cover- 90 plate for the bed-plate shown in Figs. 6 and 7.

Fig. 9 is a side edge view of the same.

Referring to the drawings wherein the invention is shown in preferred form, 1 is the frame of a folding-machine, having a bed, 2, upon which the blanks are placed 95 to be folded; a templet, 3, cooperative with said bed to hold a blank thereagainst, over the edge of which templet the edge-portions of the blank are infolded by means of infolders, 4.

The templet is mounted upon an arm, 6, fixed upon a shaft, 7, rotatively mounted in bearings in a bracket, 8, fixed upon the frame of the machine whereby the templet can be swung toward and from the bed, 1. 105

Rocking movements are imparted to the shaft, 7, for this purpose by means of a rocker-arm, 9, fixed upon said shaft, 7, projecting into the path of one end, 10, of a lever fulcrumed at 11, upon the frame of 110

the machine, the other end, 12, of which lever projects into the path of a cam, 13, fixed upon a piston-rod, 14, having upon its lower end a piston, 15, reciprocatory 5 within an air-cylinder, 16.

The folding of each blank is accomplished by a complete reciprocating movement of the piston, 15.

Compressed air may be admitted to the 10 air-cylinder, 16, in any known manner for operating the piston, 15.

Suitable connections may also be provided between the piston-rod, 14, and the infolders, 4, and bed, 2, for moving the infolders inward and outward over the bed, and for forcing the bed upward to press the folded edges of the blank between the bed and the infolders; but as these features 15 form no part of my invention and will be readily understood by those skilled in the 20 art, further description of the same is unnecessary.

In carrying out my invention in preferred 25 form, I provide the bed, 2, with an elongated spiral groove, 17, on its under side adapted to receive an electric resistance element or coil, 20, secured in said groove by means of a cover-plate, 18, attached to the underside of said bed, 2.

The cover-plate, 18, is provided with 30 apertures, 19, at various points for the passage therethrough of wires, 25, adapted to be connected with different points of the resistance coil, 20, as will be hereinafter 35 explained; and enlargements, 21, are formed in the groove, 17, in the bed, opposite the respective apertures, 19, in the cover-plate which enlargements permit said wires to be joined to the resistance coil.

40 A switch-plate, 22, is mounted upon the frame of the machine by means of a split bearing, 23, embracing a circular boss, 24, on the bracket, 8.

This switch-plate has mounted thereupon 45 a series of contacts, 26, insulated from each other, connected respectively with the wires, 25, which are joined to the resistance coil, 20, at different points in the coil.

One end 20^a, of the coil, is connected by 50 a wire, 27, with one side of an electric circuit, the other side of said circuit being connected by a wire, 28, with the other end 20^b, of said coil.

A branch wire, 29, leads from the wire, 55 28, to a contact-brush, 30, which bears upon the hub, 31, of an arm, 32, fixed upon the templet-carrying shaft from which it is insulated.

A contact-finger, 33, is adapted to make 60 sliding engagement with the successive contacts, 26, on the switch-plate, 22, as the templet is raised and lowered by rocking movement of the shaft, 7, said contact-finger being carried by said arm, 32.

65 The switch-contacts, 26, are connected by

the wires, 25, with points in the coil, 20, at successively greater distances from its end, 20^b in the order in which said contacts, 26, are successively engaged by the contact-finger, 33, as the templet is moved from its 70 raised position down upon the bed.

The wires, 27 and 28, being connected with a source of electrical energy, not shown, the current will pass through the coil, 20, serving to heat the coil, but the 75 degree to which the coil will be thus heated is limited by the resistance offered by the entire coil.

By employing a coil of proper length or 80 resistance, it is possible, so long as the current enters and leaves only at the ends of the coil, to limit the temperature of the bed, 2, to a maximum degree which is less than that at which the blanks would be scorched, and in the operation of the machine the 85 supply of heat thus contributed is substantially constant and uniform.

In the operation of the machine every 90 time the templet descends from the bed, the arm, 32, is operated causing its contact-finger, 33, to move along the series of contacts, 26.

As the contact-finger, 33, engages each successive contact, 26, in such movement, it causes the electric current to pass through 95 successively shorter lengths of the coil, 20, which shorter lengths, offering less resistance, become more highly heated.

As the machine operates on successive 100 blanks, an intermittent supply of heat is developed in certain portions of the coil in addition to the heat developed by the 105 constant and uniform supply due to the passage of the current through the whole coil, and in the operation of the machine it is intended that the heat thus supplied through the medium of the contact-finger, 33, shall be substantially the same as the 110 heat taken from the machine by the successive blanks.

Heat-units are thus imparted intermittently to the bed, 2, in substantially the 115 ratio in which heat-units are taken from said bed in the operation of the machine upon successive articles.

The maximum degree of heat is obtained therefore only as the machine is operated, and if for any reason the operation is discontinued or the speed of operation is lessened this auxiliary supply of heat will be either cut off entirely or intermittently imparted with less frequency in accordance with the speed of operation of the machine.

Thus if the machine be left idle for a time with the templet, 3, raised as shown in Fig. 4, the switch contact finger, 33, may be left in contact with the righthand end contact, 26, which is shown in Fig. 2, is connected with one end of the coil at 20^b, the other end of the coil being connected at 20^a, with the 120

opposite side of the circuit. The current thus transmitted through the coil is opposed by the whole resistance of the coil, and causes the bed to be heated to a limited degree only, 5 and less than the temperature required in the operation of the machine. As soon as the operation of the machine is resumed, however, each time the die descends the switch contact finger will be brought into 10 contact with another or others of the contacts, 26, which are connected with intermediate points in the coil thus causing the current to pass through a less extent of the coil which extent will be more highly heated 15 to impart the maximum heat to the bed.

The switch-plate, 22, is rotatively adjustable upon the templet-carrying shaft, 7, and it can from time to time be adjusted by means of a handle, 34, causing the contact-finger, 33, at the limit of the downward movement of the templet to engage such one of the contacts, 26, as may be desired.

In the drawings the switch-plate is shown in such position of adjustment that at the 25 limit of the downward movement of the templet the contact-finger, 33, engages the last in the series of said contacts, 26.

By moving the handle, 34, to the right as seen in Fig. 4, the contact-finger, 33, will 30 in its initial position be located more or less in advance of the series of contacts, 26; and in its ultimate position it will engage one of said contacts at more or less distance from the end of the series, thus causing a lesser 35 degree of heat to be imparted to the bed at each operation of the machine, than is the case when the switch-plate is in the position shown in Fig. 4.

I have shown the contact-finger, 33, actuated by, and in synchronism with the templet-carrying arm, but this is only one of the 40 many ways in which the heat can be intermittently imparted to the bed in accordance with my invention.

Any other movable member of the 45 machine may be employed for this purpose, or other suitable means employed for operating the contact-finger, 33, in synchronism with the operation of the machine upon successive blanks.

I do not wish to be limited to the particular mechanism shown for carrying out my invention as the same can be changed in many respects without departing from the 50 spirit or scope of my invention.

In Fig. 3, I have shown a gas-burner, 40, mounted beneath the bed, 2, supplied by a pipe, 41, leading from a supply of gas, or gas and air, not shown.

A valve, 42, serves as a means for regulating the constant and uniform supply of gas 60 to the burner, 40, for a normal flame.

A by-pass, 43, extends around the valve, 42, and is controlled by a valve, 44, which 65 valve, 44, is automatically operated by means

of an arm or handle, 45, having a pin-and-slot engagement with a bracket, 46, fixed upon the piston-rod, 14.

As the piston-rod descends after each folding operation the valve, 44, is automatically 70 closed.

As the piston-rod rises in synchronism with the downward movement of the templet, the valve, 44, is opened permitting an additional supply of gas to pass around the 75 valve, 42, to the burner, 40, to cause a greater flame, whereby additional heat-units are intermittently imparted to the bed in substantially the ratio in which heat-units are taken from the bed in the operation of the 80 machine upon successive articles.

While I have shown my invention in its application to the heated bed of a folding-machine, it will be understood that it is also applicable to any other part of the folding-machine which requires to be heated as well 85 as to the parts of other machines used under similar conditions for the treatment by heated members of a series of articles.

If it be desired to quickly heat the bed, 90 2, preparatory to starting the operation of the machine, the switch-plate, 22, can by means of the handle, 34, be moved to the right as shown in Fig. 4, to bring the contact-finger, 33, into engagement with such of 95 the contacts, 26, as will produce quickly the desired degree of heat.

After the bed has been thus preliminarily heated, the switch-plate, 22, can be moved 100 back to its normal position.

For the purpose last stated the switch comprising the switch-plate, 22, contacts, 26, and contact-finger, 33, may be located in any convenient position.

For certain purposes of the invention, it 105 is characteristic of my invention that in the operation of the machine the intermittent movement of the die and of the arm, 32, intermittently opens and closes a shunt circuit with respect to the main circuit whereby heat units are transmitted continuously (but not necessarily uniformly) to the whole coil, which shunt circuit shunts more or less of the coil as may be desired. If this shunt circuit be made to shunt limited portions only of the coil, the remainder of the 110 coil will intermittently receive an additional supply of heat units as above described.

If the shunt circuit shunts the whole coil, then the whole coil will intermittently receive such additional supply of heat units. In the construction shown in Fig. 3, the by-pass, 43, serves as a shunt for the gas supply, whereby an additional supply of heat units is intermittently transmitted to 120 the gas-heater.

What I claim as new and desire to secure by Letters Patent is—

1. In a machine of the class described and in combination, a heater; means for trans- 130

mitting to said heater a continuous supply of heat units; shunt means with respect to said means for supplying heat units, for supplying additional heat units to more or less of said heater; and automatic means for intermittently controlling the supply through said shunt means in the operation of the machine.

2. In a machine of the class described and in combination, a member movable in the operation of the machine; a heater; means for transmitting to said heater a continuous supply of heat units; shunt means with respect to said means for supplying said heat units, for supplying additional heat units to more or less of said heater; and automatic means for intermittently controlling the supply through said shunt means in synchronism with movements of said movable member.

3. In a machine of the class described and in combination, an electric heater having a resistance; means for transmitting to said resistance a continuous supply of electric current in the operation of the machine; a switch-controlled shunt-circuit with respect to more or less of said resistance; and automatic means whereby said shunt-controlling switch is intermittently operated.

4. In a machine of the class described and in combination, a member movable in the operation of the machine; an electric heater having a resistance; means for transmitting to said resistance a continuous supply of electric current in the operation of the ma-

chine; a switch-controlled shunt circuit with respect to more or less of said resistance; and automatic means whereby said shunt-controlled switch is intermittently operated in synchronism with movements of said movable member of the machine.

5. In a machine of the class described having a member movable in the operation of the machine, the combination with an electric heater having a resistance; means for transmitting to said resistance a constant supply of electric current during the operation of the machine; switch-controlled means for transmitting to a part only of said resistance a supply of electric current independently of said constant supply; and automatic means whereby said switch is intermittently operated by said movable member of the machine.

6. In a machine of the class described having a member movable in the operation of the machine, the combination with an electric heater; of means for transmitting a constant supply of electric current to said heater in the operation of the machine; switch-controlled means for transmitting to part only of said heater a supply of electric current independently of said constant supply; and automatic means whereby said switch is intermittently operated by said movable member of the machine.

In testimony whereof, I have hereunto set my hand this 3rd day of April, 1917.

ROY S. LATIMER.
